SPIRAL PACKED WORKING BARREL VALVE
BODY

William H. Hunter, Webb City, Mo.

Application January 30, 1936, Serial No. 61,604

5 Claims. (Cl. 103—225)

This invention relates to a valve body for working barrels of the kind used in lift or beam or any type of hydraulic plunger pumps and it generally aims to provide a novel packing means therefor which will be effective at all times, automatically compensate for wear and be expeditiously applied.

It is further aimed to provide such a packing means which will be maintained effective by a fluid pressure and vacuum within the pump.

The more specific objects and advantages will become apparent from a consideration of the description following taken in connection with the accompanying drawing illustrating an operative embodiment.

In said drawing:—

Figure 1 is a view in elevation of a working barrel valve body equipped with my improvement;

Figure 2 is a fragmentary longitudinal sectional view of said valve;

Figure 3 is a horizontal sectional view taken on the plane of line 3—3 of Figure 1;

Figure 4 is a horizontal sectional view taken on the plane of line 4—4 of Figure 1;

Figure 5 is a perspective view of one end of a packing strip and

Figure 6 is a perspective view of the opposite end of said strip.

Referring specifically to the drawing wherein like reference characters designate like or similar parts, 10 designates a working barrel valve body of any desired size or kind, for a conventional lift or beam or hydraulic plunger pumps in accordance with my invention, the exterior of such valve 10 is provided with one or more spiral grooves 11 of any desired extent and preferably square in cross section as shown. Such grooves at the opposite ends are overlapped by walls or plates 12 and 13, such plates for instance being welded to the body 10. Leading from the bore of the body 10 and communicating with the bases of the grooves 11 are orifices or openings 15, the latter being of any desired number and preferably being relatively close together.

Fitting the grooves 11 normally flush with the periphery of the body 10, are strips of packing 16. Such strips 16 are square in cross section, preferably, and are of any suitable flexible material, for instance being composed of a plurality of sheets or plies riveted together at intervals as at 17 to prevent separation. Such plies may be of textile fabric or they may be such fabric impregnated with rubber, or instead they may be of any other packing material. At one end, such

strips 16 have reduced tongues 18 fitting intimately beneath the plates 13 and being anchored to the body by means of screws 19 passing through such plates 13, tongues 18 and being threaded into the body 10 proper.

At the opposite ends, strips 16 have reduced portions or tongues 20, provided with elongated slots 21. Screws 22 pass through the plates 12, slots 21 and are screwed into the body 10 proper. Initially the innermost ends of the slots 21 are in contact with screw 22 and a pin 23 passes through registering openings to plate 12, tongue 20 and valve 10 proper, as shown in Figure 3. This pin 23 is relatively frail so as to be fractured or broken through expansion and elongation of the packing strip.

In the use of the device, the valve body 10 is positioned with the strips in the position shown in the drawing, flush with the periphery of valve body 10, and anchored by the pins 23. Thereafter when the strips are subjected to the oil or liquid being pumped, pins 23 will be fractured and the strips permitted to move in the grooves, toward the anchors 19, to the extent permitted by the length of the slots 21. The packing to some extent absorbs the liquid. In addition, the suction incidental to operation and the pressure passing through the openings 15, maintains the packing in effective engagement with the cylinder or working barrel for the body 10, such packing being drawn to the anchored ends 19 automatically, as required, and also to take up wear.

The valve body 10 on the exterior thereof, between the grooves 11, is preferably flattened as at 24 to facilitate engagement by a wrench or turning tool.

Various changes may be resorted to provided they fall within the spirit and scope of the invention.

I claim as my invention:—

1. A valved piston body of the class described having spiral packing grooves, packing strips disposed in said grooves, said valve body having openings leading to said grooves through which hydrostatic pressure in said body acts to expand said packing, means anchoring each strip at one end of each of said grooves and the strip being slip-connected in the grooves at their other ends.

2. A valved piston body of the class described having spiral packing grooves, packing strips disposed in said grooves, said valve body having openings leading to said grooves through which hydrostatic pressure in said body acts to expand said packing, means anchoring each strip at

one end of each of said grooves and the strip being slip-connected in the grooves at their other ends, and plates at opposite ends of said grooves beneath which the strip is disposed.

5. A valved piston body of the class described having spiral packing grooves, packing strips disposed in said grooves, said valve body having openings leading to said grooves through which hydrostatic pressure in said body acts to expand 10 said packing, means anchoring each strip at one end of each of said grooves and the strip being slip-connected in the grooves at their other ends, plates at opposite ends of said grooves beneath which the strips are disposed, the plate at one 15 end of each of the grooves having a fastening therethrough, and each strip having an elongated slot through which the fastening passes.

4. A valved piston body of the class described having spiral packing grooves, packing strips 20 disposed in said grooves, said valve body having openings leading to said grooves through which hydrostatic pressure in said body acts to expand said packing, means anchoring each strip at one end of each of said grooves and the strip being 25 slip-connected in the grooves at their other ends, plates at opposite ends of said grooves beneath

which the strips are disposed, the plate at one end of each of the grooves having a fastening therethrough, each strip having an elongated slot through which the fastening passes, and fracturable means initially anchoring the last mentioned 5 end of each strip in the groove containing the strip.

5. A valved piston body of the class described having spiral packing grooves, packing strips disposed in said grooves, said valve body having 10 openings leading to said grooves through which hydrostatic pressure in said body acts to expand 15 said packing, means anchoring each strip at one end of each of said grooves and the strip being slip-connected in the grooves at their other ends, plates at opposite ends of said grooves beneath which the strips are disposed, the plate at one end of each of the grooves having a fastening therethrough, each strip having an elongated slot through which the fastening passes, and fracturable means initially anchoring the last mentioned 20 end of each strip in the groove containing the strip, and means anchoring the other end of the strip in the groove, one of said means being fracturable through elongation of the strip. 25

WILLIAM H. HUNTER.
